SPOON OR SIMILAR ARTICLE

John W. W. Creke, Sheffield, England, assignor to Cooper Bros. & Sons Limited, Sheffield, England

Application June 30, 1949, Serial No. 3,650
In Great Britain March 1, 1949

Term of patent 14 years

(Cl. D54—12)

To all whom it may concern:

Be it known that I, John William Wakefield Creke, a subject of the King of Great Britain and Northern Island and residing at Sheffield, England, have invented a new, original, and ornamental Design for a Spoon or Similar Article, of which the following is a specification, reference being had to the accompanying drawing, forming part thereof.

Fig. 1 is a side elevational view of a spoon or similar article, showing the essential features of my new design in full lines.

Fig. 2 is a front face elevational view of the spoon or similar article shown in Fig. 1.

Fig. 3 is a cross sectional view taken on line 3—3 of Fig. 2.

The essential features of my design reside in the contour of the handle and the ornamentation thereon. The design is intended for use on sets comprising spoons, forks, knives, and similar articles of tableware.

I claim:

The ornamental design for a spoon or similar article, as shown and described.

JOHN W. W. CREKE.
